UNITED STATES PATENT OFFICE.

PAUL HARI, OF PORTLAND, OREGON, ASSIGNOR, BY DIRECT AND MESNE ASSIGNMENTS, TO OREGON ENVELOPE COMPANY, A CORPORATION OF OREGON.

ENVELOP.

1,104,298.

Specification of Letters Patent.

Patented July 21, 1914.

Application filed December 8, 1913. Serial No. 805,389.

To all whom it may concern:

Be it known that I, PAUL HARI, citizen of the Republic of Switzerland, residing at Portland, in the county of Multnomah and 5 State of Oregon, have invented certain new and useful Improvements in Envelops, of which the following is a specification.

This invention relates to envelops of the kind particularly adapted for inclosing letters or papers, and pertains more especially 10 to the provision of means for effecting the opening thereof.

The primary object of the invention is to provide an envelop which may be readily 15 opened without having to resort to the use of means or devices foreign thereto, the structure for effecting this result being embodied in the envelop itself.

A further object of this invention is to 20 provide an envelop of the above described character which may be cheaply manufactured, the opening means employed being capable of incorporation into the envelop as it is manufactured and without the necessity of any additional manual labor.

A further object of the invention is to 25 provide an envelop wherein the opening means employed may be readily observed and easily grasped for operation by the person receiving the envelop.

A further object of this invention is to so 30 position the opening means in the envelop that it will not become entangled or interfere with the operation of cancelling machines.

A still further object of this invention is to so construct the envelop that the opening means may be readily attached thereto in 35 position before the blank is pasted, such construction also serving to effectually secure said means in the finished envelop. And a still further object of the invention is to generally improve and increase the efficiency of devices of the above described character.

40 For a full understanding of the invention, reference is to be had to the following description and accompany drawing, in which:

Figure 1 is a perspective view of my improved envelop. Fig. 2 is a perspective 45 view of the envelop showing the cutting thread in position thereon before posting of the blank. Fig. 3 is a fragmentary perspective view of a modified form of my invention.

50 Corresponding and like parts are referred

to in the following description and indicated in all the views of the accompanying drawings by the same reference characters.

Referring to the drawings, the numeral 1 designates an envelop blank which includes 60 a side flap 2, back flap 3, which, preferably, is substantially rectangular, end flaps 4, which, preferably, are also substantially rectangular in shape, and a sealing flap 5. Secured within the envelop between the inner 65 face of the side flap and the inner face of one end flap and extending transversely thereof, is a cutting thread or string 6. I am aware that such means have previously been employed to effect the opening of 70 envelops, but usually the string has been so arranged upon the envelop as to be not easily or ordinarily observed by the person receiving the envelop and therefore fails in its intended purpose. Furthermore, to place the 75 string in the envelop as heretofore manufactured, has been found to so increase the cost thereof, owing to the difficulty of retaining the string in position prior to initial pasting, as to make the use of this type of envelop 80 exceedingly limited. The string has also not been effectually secured to the envelop resulting in its disengagement therefrom without the accomplishment of the object intended. To overcome these disadvantages, I 85 have arranged the cutting thread 6 within one end flap, as stated, and closely against the fold thereof, the upper extremity of the string being looped to define a retaining portion 7 which extends over the upper edge 8 90 of the flap and diagonally across the outer face toward the side thereof where it is secured between the adhering gummed faces of the end and side flaps, the angular disposition of said retaining portion insuring that 95 the thread will extend well within the gum surfaces. The free end 9 of the thread 6 is designed to project beyond the lower edge of the envelop opposite the mouth thereof where it may be easily grasped for operation. It should be observed that in thus disposing the cutting thread within the envelop, the free end thereof cannot be obscured in the sealing operation, a difficulty 100 heretofore experienced with envelops of similar character. Furthermore, the free end of the thread is so disposed as to not interfere with postage affixing or canceling machines, an advantage clearly obvious.

To open the envelop the free end 9 of the 110

cutting thread should be grasped and an upward pull exerted thereon when the thread will be caused to cut or sever the portion forming the end of the envelop along the line of the fold. Attention is here called to the fact that any stress tending to disengage the fixed end of the cutting thread from the envelop during the cutting operation will not come directly upon the retaining portion 7 but will be supported by the upper edge 8 of the end flap, said edge forming a bearing shoulder for the thread. As will be clearly apparent, the stress upon said flap will be longitudinally thereof and any tendency of the upper end of the flap to buckle or move laterally will be counteracted by the adjacent side and back flaps. A support of considerable rigidity is accordingly provided for the fixed terminal of the thread. However, the retaining portion 7 owing to its angular disposition will be in alinement with the line of pull upon the thread after the envelop has been opened and consequently will be readily disengaged to entirely free said thread therefrom.

In Fig. 3, I have illustrated a modified form of my invention in which one end flap 4 has formed in its vertical edge, near the upper end thereof, an inwardly directed and outwardly extending V-shaped notch 10. Said notch is designed to aline with the angular direction of the retaining portion 11 and is adapted to engage the extremity 12 thereof. In the manufacture of the envelop, one extremity of the cutting thread may be inserted in the notch when an inward pull will serve to effect engagement therewith. The thread may then be positioned about the end flap where it will be held in place pending the pasting of the blank. Furthermore, this notch serves to more effectually secure the retaining portion 11 to the envelop. Such engagement, however, will not prevent the ready disengagement of the thread by the same movement required to open the end of the envelop. In Fig. 3, I have also illustrated a further modification of my invention consisting in sinuously disposing that portion of the cutting thread lying within the end flap, as shown at 13. In this construction only a small portion of

the thread constituting the free end 14 will project from the envelop, a slight downward pull thereon being sufficient to straighten the sinuously disposed portion of the thread resulting in a lengthening of the free end which may then be readily grasped to open the envelop.

Having thus described the invention, what is claimed as new is:—

1. In an envelop, having an end flap and a back flap adhering to the face of one extremity of the end flap, a cutting thread positioned within the fold of the end flap, one extremity of the thread being looped over one edge of the end flap and extending diagonally of the outer face thereof the portion looped over terminating adjacent the free side edge of the flap and being secured between the adhering gummed faces of the end and back flap the free end of the thread projecting beyond the opposite edge of the envelop and forming a free terminal.

2. In an envelop having an end flap and a back flap adhering thereto, a sinuously disposed cutting thread positioned within the end flap, one extremity of the thread being secured to the envelop and the opposite extremity thereof extending to form a free terminal.

3. In an envelop having an end flap and a back flap adhering to the face of one extremity of the end flap, a cutting thread positioned within the end flap and being sinuously disposed throughout a portion of its length, one extremity of the thread being looped over one end edge of the end flap to extend diagonally of the upper extremity thereof and being secured between the adhering gummed faces of the side and end flap, an inwardly directed obliquely disposed V-shaped slot formed in the free edge of the end flap, and arranged to engage the extremity of the looped over portion of the thread, the free end of the thread projecting beyond the opposite edge of the envelop and forming a free terminal.

In testimony whereof I affix my signature in presence of two witnesses.

PAUL HARI. [L. s.]
